UNITED STATES PATENT OFFICE.

HARRY A. MAYBERRY, OF MCLEANSBORO, ILLINOIS.

AUTOMOBILE RADIATOR CAP.

Application filed March 7, 1922. Serial No. 541,808.

To all whom it may concern:

Be it known that I, HARRY A. MAYBERRY, a citizen of the United States, and a resident of McLeansboro, in the county of Hamilton and State of Illinois, have invented a new and useful Automobile Radiator Cap, of which the following is a specification.

My invention relates to automobile radiator caps and its principal object is to provide a radiator cap which will permit the radiator to be filled with water without removing the cap from the radiator.

A further object of the invention is to provide a radiator cap provided with a valve normally urged to closed position and adapted to be moved to open position upon pressing the nozzle of a hose thereagainst, thus the necessity of removing the cap from the radiator is obviated.

Still another object of the invention is to provide a radiator cap which will be universal to all automobile radiators and which, at the same time, will be inexpensive and practical in use.

With the preceding and other objects and advantages in mind, the invention consists in the novel combination of elements, construction and arrangement of parts and operations to be hereinafter more fully described, claimed and illustrated in the accompanying drawing, in which:

Figure 1 is a plan view of the radiator cap;

Figure 2 is a side elevation of the cap mounted on the nipple of a radiator;

Figure 3 is a vertical sectional view of the same; and

Figure 4 is a bottom plan view of the device.

Referring in detail to the drawing wherein similar characters of reference designate similar parts throughout the several views, the numeral 5 designates the usual threaded nipple of an automobile radiator while the numeral 6 designates the cap threaded thereon. The cap 6 is provided with a central opening 7 in which a valve 8 is normally engaged. In order to limit the upward movement of the valve 8, the cap 6 is provided with an annular flange 9 that surrounds the opening while the valve 8 is formed with an annular flange 10 for abutment with the flange 9.

Disposed within the cap is a pair of U-shaped members 11 arranged at right angles to each other and integrally joined at their centers. The legs of these U-shaped members 11 are formed with laterally disposed ears 12 at their ends which are secured to the upper wall of the cap 6 by removable fastenings 13.

An expandible coil spring 14 is supported on the U-shaped members and has its lower end riveted to the latter, as indicated at 15. The upper end of this spring 15 is turned at right angles and embedded in the under face of the cap as shown at 16. In order to prevent the valve 8 from having any tendency to shift laterally with respect to the coil spring 14 when the former is in unseated position, a depending annular flange 17 extends from the under face of this valve 8 and overlies the upper convolutions of the spring 14.

The upper face of the valve 8 is formed with upstanding radially disposed ribs 18 against which the mouth of the nozzle of the filling hose is adapted to be engaged to space the latter from the upper face of the valve 8 so that the water may pass freely from the nozzle.

In operation, it will be obvious that upon pressing the nozzle of a filling hose against the ribs 18, the valve 8 will be moved downwardly, away from its seat, against the tension of the spring 14. After disengagement of the nozzle from the ribs 18 of the valve 8 will be returned to closed position by the coil spring 14.

It is to be understood that the form of my invention herein shown and described is to be taken as a preferred example of the same, and that various changes in the shape, size and arrangement of parts may be resorted to without departing from the spirit of the invention or the scope of the subjoined claim.

Having thus described my invention, what I claim as new and desire to secure and protect by Letters Patent of the United States, is:—

A closure having a central opening, a valve normally seated in the opening, a pair of U-shaped members arranged at right angles to each other, each provided with an extension at its upper end, said extensions secured to the underface of the closure, a

coil spring having convolutions of substantially the same area as the area of the valve and engaged with the under face of the valve, the lower end of the coil spring being 5 extended through the U-shaped members at its places of intersection and formed with a head wherein the lower end of the spring is held against lateral movement, and a depending flange carried by the under face of the valve and receiving the top convolution ¹⁰ of the spring, whereby this end of the spring is held against lateral movement.

HARRY A. MAYBERRY.
